The present invention is concerned with a process for the manufacture of O,O-dialkylthionophosphoric acid chlorides having the general formula:

in which R stands for an alkyl radical having 1 to 6 carbon atoms.

It is known that O,O-diethylthionophosphoric acid chloride can be prepared by a two step process wherein, in a first process step, phosphorus pentasulfide is caused to react with ethanol according to the following equation:

so as to form O,O-diethylthiophosphoric acid and hydrogen sulfide and wherein, in a second process step, the isolated O,O-diethylthiophosphoric acid is chlorinated in an appropriate solvent with chlorine gas according to the following equation:

The O,O-diethylthionophosphoric acid chloride prepared in conventional manner is obtained with a maximum yield of 70%, related to the amount of O,O-diethylthiophosphoric acid obtained in the first process step.

This conventional method is beset with various disadvantages. Firstly, the hydrogen sulfide formed in the first process step as a by-product must be rendered harmless by specific means. Secondly, the work-up of the disulfur dichloride obtained in the second process step is difficult to achieve and expensive. Thirdly, the chlorination reaction according to Equation II is strongly exothermal and sometimes proceeds in explosion-like manner, so that care must always be taken to ensure good cooling of the reaction mixture.

The present invention obviates the above disadvantages by providing a process wherein the work-up of resulting by-products and special cooling of the reaction mixture may be omitted. Furthermore, the process is carried out in a single step with the use of a readily available and commercially cheap starting product.

The process of the present invention for making O,O-dialkylthionophosphoric acid chlorides having the general formula:

in which R stands for an alkyl radical having 1 to 6 carbon atoms is basically carried out according to the following reaction equation:

2

The process of the present invention comprises introducing a stream of chlorine gas into a P_2S_5 -suspension in an inert solvent at a temperature within the range of about 0 to 150° C. and adding dropwise concurrently therewith an alcohol having 1 to 6 carbon atoms, allowing the reaction to proceed to completion, expelling the solvent, and isolating O,O-dialkylthionophosphoric acid chloride from the reaction mixture by subjecting it to distillation.

In determining the reaction conditions applicable to the process of the present invention it has been found advantageous to react the phosphorus pentasulfide serving as the feed with a suitable alcohol and chlorine gas in a definite molar ratio of 1:4.0 to 4.4:2.2 to 3.2. The proportion of chlorine used, i.e. 2.2 to 3.2 mols per mol phosphorus pentasulfide, is especially important since outside this range the yield of O,O-dialkylthionophosphoric acid chlorides will drop. For making O,O-dimethylthionophosphoric acid chloride, for example, the P_2S_5 , alcohol and chlorine should be used in a molar ratio of 1:4.0 to 4.4:2.2 to 2.7, preferably of 1:4.4:2.4.

It has also been found that the yield of O,O-dialkylthionophosphoric acid chlorides is influenced by the proportion of alcohol and chlorine added per unit of time to the phosphorus pentasulfide suspension. Maximum yields are obtained by adding the chlorine gas to the phosphorus pentasulfide suspension in an inert solvent in such a way that about half of the calculated chlorine quantity has been introduced thereinto once the total amount of alcohol has been added. In other words, chlorine and alcohol are introduced at a feed rate or speed of approximately 1:2. The balance chlorine portion is then introduced continuously at a constant feed rate into the suspension. Introduction of the chlorine gas either after the addition of the total amount of alcohol or at a feed rate the same as the alcohol will result in reduced yields.

It has also been found that the yields are a function of the temperature used in the process of the present invention, i.e. that by maintaining a reaction temperature of about 70 to 90° C. within the interesting range of about 0 to 150° C. is most advantageous.

A further feature of the present invention resides in the use of an inert solvent for making the necessary phosphorus pentasulfide suspension. The inert solvents useful for this include e.g. toluene, xylene, carbon tetrachloride, petroleum ether (B.P.: 65–95° C.) or the like as well as the O,O-dialkylthionophosphoric acid chloride obtained as the reaction product.

The alcohols useful for use in carrying out the process of the present invention include e.g. methanol, ethanol, propanol, iso-propanol, n-butanol, iso-butanol, amyl alcohol, hexyl alcohol and the isomers thereof.

The process of the present invention is generally carried out by charging an appropriate reaction vessel with approximately equal parts by weight of phosphorus pentasulfide and inert solvent, stirring the material in the vessel so as to obtain a suspension, gradually admixing the suspension with a suitable alcohol and chlorine gas, the chlorine gas being introduced in such a way that about half of the calculated chlorine quantity has undergone reaction once the total amount of alcohol has been added to the suspension. The chlorine balance portion is introduced subsequent to the alcohol addition while maintaining the initial rate of flow. During the entire reaction time, the reaction temperature is maintained e.g. at 70° C. by slight heating or slight cooling as the case may be. Once the chlorine addition has been terminated, the reaction mixture is first freed from the inert solvent, and O,O-dialkylthionophosphoric acid chloride is then distilled off, preferably under reduced pressure. During such treatment, the temperature in the sump portion of the reaction vessel may increase to about 150° C. The remaining

liquid sump phase solidifies on cooling and consists substantially of elementary sulfur.

It has also unexpectedly been found that the yields can be further improved by introducing into the reaction mixture diluted chlorine gas, i.e. chlorine gas in admixture with an inert gas, e.g. carbon dioxide and argon, preferably nitrogen, in a ratio by volume of about 1:0.5 to 1:3.

Still further, it has proved advantageous to use about 1 to 2 liters, preferably 1.5 liters solvent per kg. P_2S_5 .

In contrast to the art holding O,O -dialkylthionophosphoric acid chlorides to undergo explosion-like reaction with water at $60^\circ C$, it has been found that these compounds can be purified without undergoing decomposition in easy and harmless manner by being subjected to steam distillation.

The process of the present invention taken as a whole offers a series of characteristic advantages over customary methods. Firstly, it enables the desired process product to be prepared in a single process step, the necessary feed product being readily available and relatively cheap. Secondly, the reaction of the phosphorus pentasulfide with alcohol and chlorine gas is but slightly exothermal and therefore requires no cooling steps in the absence of any danger of explosion. Furthermore, any expensive work-up or destruction of by-products is obviated because the sulfur obtained as the distillation residue is useful for further application. Still further, the dialkylthionophosphoric acid chloride prepared by the process of the present invention is obtained in yields of more than 90%, related to the dialkyldithiophosphoric acid formed as an intermediary product, i.e. in yields considerably higher than those obtained by conventional methods.

The following examples serve to illustrate the invention, but they are not intended to limit it thereto:

Example 1

1.11 kg. phosphorus pentasulfide were suspended while stirring in 1 liter toluene which had been placed into a 4-liter four-necked flask, and the suspension was admixed within 100 minutes with 1,285 liters ethanol and 532 grams, i.e. the half of the necessary chlorine gas. Once the alcohol had been added, a further 532 grams chlorine gas were caused to react with the phosphorus pentasulfide which had meanwhile dissolved. During the whole reaction time, the temperature was maintained at $70^\circ C$. by slight heating or slight cooling. After the chlorine had been added, the toluene was expelled from the reaction mixture and diethylthionophosphoric acid chloride was distilled off at $68^\circ C$. and under a pressure of 8 mm. mercury. The remaining liquid distillation residue was first heated at a sump temperature of $150^\circ C$., then cooled and the residue which consisted substantially of elementary sulfur was allowed to solidify.

1360 grams diethylthionophosphoric acid chloride having a refractive index of $n_D^{25}=1.4690$ were obtained corresponding to a yield of 73%, calculated on the amount of phosphorus pentasulfide used. The product obtained had a degree of purity of 99.3% as determined by gas-chromatographic analysis.

Example 2

In a manner analogous to that described in Example 1, 222 grams phosphorus pentasulfide were suspended while stirring in 194 cc. toluene placed in a 1-liter four-necked round flask, and the suspension was admixed in the course of 100 minutes with 187 cc. methanol. During the methanol addition, 107 grams chlorine gas were introduced followed by the introduction of a further 107 grams chlorine gas during a further 100 minutes period of time. During the reaction, the reaction temperature was at about $70^\circ C$. After the necessary amount of chlorine gas had been introduced, the toluene was expelled from the reaction mixture and dimethylthionophosphoric acid chloride was distilled off under a pressure of 16 mm. mercury at a temperature of $61^\circ C$. 210 grams dimethylthionophosphoric acid chloride were obtained, corresponding to a

yield of 65% related to the amount of phosphorus pentasulfide used. The product so prepared had a refractive index of $n_D^{25}=1.4805$.

Example 3

5 In a manner analogous to that described in Example 1, 222 grams phosphorus pentasulfide were suspended while stirring in a 1-liter four-necked round flask in 194 cc. toluene and the resulting suspension was admixed within 100 minutes with 404 cc. n-butanol. During the butanol 10 addition, 107 grams chlorine gas were introduced and thereafter a further 107 grams chlorine gas again within 100 minutes. The reaction temperature was at about $90^\circ C$. The toluene was expelled from the reaction mixture and dibutylthionophosphoric acid chloride was distilled 15 off at a pressure of 5 mm. mercury at a boiling temperature of $107^\circ C$. 293 grams dibutylthionophosphoric acid chloride were obtained. This corresponded to a yield of 60% related to the amount of phosphorus pentasulfide used. The product so prepared had a refractive index of $n_D^{25}=1.4670$.

Example 4

The apparatus was a 20-liter glass flask provided with a stirring means and 4 inlet sockets, of which each 25 socket was intended respectively to serve as methanol supply, gas admission, reflux condenser and temperature determination. The reflux condenser had an internal width of 80 mm. and was packed over a length of 1 meter with saddle-shaped packing material. The gas admission line was a T-piece serving to supply chlorine and nitrogen. The glass flask was placed in a metal trough having joints for supplying cooling water and hot steam. 5.55 kg. P_2S_5 were suspended while stirring in 7.8 liters CCl_4 in the flask and 4.45 liters CH_3OH were added. At the start 30 of the reaction, the flask had to be cooled with some water. The reaction material was maintained at a temperature of 40 to $50^\circ C$. and a mixture of 350 l./hr. Cl_2 and 350 l./hr. N_2 was introduced thereto. The chlorine was used in a proportion corresponding to a molar ratio 35 of $P_2S_5:Cl_2=1:2.5$.

After the chlorine addition, the hydrogen chloride appearing in the reaction product was expelled with nitrogen in the course of 30 minutes.

The above batch gave 15.385 kg. reaction sump. An 45 aliquot portion of 1.381 kg. was distilled. 360 grams yellow-colored CCl_4 were withdrawn at a temperature of 60 to $70^\circ C$. in the still portion and under a pressure of 20-80 mm. mercury. 598 grams yellow-colored crude product were obtained under reduced pressure of 5 mm. 50 mercury and a maximum still temperature of $110^\circ C$. The crude product was hydrolyzed for $\frac{1}{2}$ hour with 200 cc. water at $30^\circ C$. and then separated in a separating funnel into two phases. The lower phase (533 grams) was again rectified under reduced pressure. 535 grams pure O,O -dimethylthionophosphoric acid chloride were obtained. Calculated on the whole batch, this corresponded to a 74.5% yield of O,O -dimethylthionophosphoric acid chloride, related to P_2S_5 .

The crude product can be hydrolyzed and purified in 60 a single step by subjecting it to steam distillation. In this case, the final product, i.e. the acid chloride, was again obtained in the form of a clear, water-white liquid.

We claim:

1. A process for the manufacture of O,O -dialkylthionophosphoric acid chlorides having the general formula:

70 in which R stands for an alkyl radical having 1 to 6 carbon atoms, which comprises reacting a phosphorus pentasulfide suspension in an inert solvent at a temperature within the range of about 0 to $150^\circ C$. with chlorine and an 75 alcohol having 1 to 6 carbon atoms by introducing a

stream of chlorine into the said suspension and adding dropwise concurrently therewith the alcohol, allowing the chlorinating reaction to proceed to completion, expelling the said solvent from the resulting reaction mixture and isolating O,O-dialkylthionophosphoric acid chloride by distillation.

2. A process as claimed in claim 1, wherein the inert solvent is at least one member selected from the group consisting of toluene, xylene, carbon tetrachloride, a petroleum ether having a boiling point of 65 to 95° C., and the O,O-dialkylthionophosphoric acid chloride obtained as the final product.

3. A process as claimed in claim 1, wherein phosphorus pentasulfide is reacted with the alcohol and the chlorine gas in the molar ratio of 1:4.0 to 4.4:2.2 to 3.2.

4. A process as claimed in claim 3, wherein the phosphorus pentasulfide, the alcohol and the chlorine are used in a molar ratio of 1:4.0 to 4.4:2.2 to 2.7 so as to prepare O,O-dimethylthionophosphoric acid chloride.

5. A process as claimed in claim 4, wherein the molar ratio of P₂S₅:alcohol:chlorine amounts to 1:4.4:2.4.

6. A process as claimed in claim 1, wherein the phosphorus pentasulfide is reacted with the alcohol and the chlorine gas at a temperature within the range of about 70 to 90° C.

7. A process as claimed in claim 1, wherein the phosphorus pentasulfide suspension in the inert solvent is admixed with the chlorine gas and the alcohol at a feed rate of approximately 1:2.

8. A process as claimed in claim 1, wherein the phosphorus pentasulfide and the inert solvent are used in about equal parts by weight.

9. A process as claimed in claim 8, wherein about 1 to 2 liters solvent are used per kg. P₂S₅.

10. A process as claimed in claim 9, wherein 1.5 liter solvent is employed per kg. P₂S₅.

11. A process as claimed in claim 1, wherein chlorine gas diluted with an inert gas is introduced into the reaction mixture.

12. A process as claimed in claim 11, wherein the inert gas is at least one member selected from the group consisting of nitrogen, carbon dioxide and argon.

13. A process as claimed in claim 11, wherein the chlorine gas is mixed with the inert gas in a ratio by volume of 1:0.5 to 1:3.

14. A process as claimed in claim 1, wherein the O,O-dialkylthionophosphoric acid chloride is isolated from the reaction mixture by distillation under reduced pressure.

15. A process as claimed in claim 1, wherein the final product obtained is purified by being subjected to steam distillation.
